J. R. SPENCER.

WRINGER,

APPLICATION FILED JUNE 5, 1920.

1,413,195.

Patented Apr. 18, 1922.

UNITED STATES PATENT OFFICE.

JOHN R. SPENCER, OF ERIE, PENNSYLVANIA, ASSIGNOR TO HOGAN-SPENCER-
WHITLEY COMPANY, OF ERIE, PENNSYLVANIA, A CORPORATION OF PENN-
SYLVANIA.

WRINGER.

1,413,195.

specification of Letters Patent. Patented Apr. 18, 1922.

Application filed June 5, 1920. Serial No. 386,698.

To all whom it may concern:

Be it known that I, JOHN R. SPENCER, a citizen of the United States, residing at Erie, in the county of Erie and State of Pennsylvania, have invented new and useful Improvements in Wringers, of which the following is a specification.

In the use of wringers, particularly power wringers, a drip board is usually provided which carries the drip from one side to the other of the wringer depending on the direction from which the clothes are fed to the wringer. Such drip boards are ordinarily manually actuated and controlled and if the operator neglects to shift the board or to lock it in position after shifting there is a deflection of the water which is discharged from the clothing at the discharge side of the wringer with a consequent inconvenience.

With this invention the drip board is automatically swung to carry the water in the right direction.

The invention is illustrated in the accompanying drawings as follows:

Fig. 1 shows an end view, partly in section, of the wringer embodying the invention.

Fig. 2 a front elevation of the wringer, partly in section.

1 and 2 mark the side stiles, 3 the top bar and 4 the cross bar. These are of the ordinary construction. The wringer is provided with the usual upper roll 5 and lower roll 6. These rolls are mounted on the shafts 7 and 8 respectively and are journaled in the bearings 9 and 10 carried by the stiles 1 and 2. The bearings 9 are slidingly mounted as is common in the slots 11 and are subjected to the pressure of springs 12 arranged in the slots. The shaft 8 has an extension 13 to which the power is applied and the opposite end of the shaft is provided with the usual gear 14 which meshes with the gear 15 on the shaft 7. A stationary drip board 16 is provided and forms as is common the connection between the lower ends of the stiles. A tilting board 17 is mounted on a shaft 18. One end of the shaft 18 extends into a perforation 19 in the stile 2. The opposite end of the shaft extends through a slot 20 in the stile 1 and is supported in a bearing 21. The bearing 21 has an extension 22 which is slidingly mounted in a

guide opening 23 in a bracket 24 secured to

the side of the frame, the bracket forming the usual housing for the gears and mechanism. A shoulder 25 is formed between the bearing 21 and the extension 22 and a spring 26 is arranged around the extension 22 and rests on a part of the bracket 24 immediately above the guide opening and against the shoulder 25 and thus yieldingly presses the shaft 18 upwardly.

A friction roll 27 is fixed on the shaft 18 and operates against a friction roll 28 fixed on the shaft 8. The roll 27 has the stops 29 and the stops 30 are arranged in the bracket in the path of the stops 29. The relative distance between the stops 30 and the stops 29 permits of a movement of the roll 27 through a sufficient number of degrees to give the proper movement to the drip board 17 carried by the shaft 18.

The operation of the device is as follows:—With the wringer moving in one direction the frictional engagement of the roll 28 with the roll 27 drives the roll 27 and with it the shaft 18 in a direction to tilt the drip board 17 toward the feeding side of the rolls. When the rolls are reversed the frictional drive rotates the roll 27 and with it the shaft 18 so as to reverse the board 17, the stops 29 operating in connection with the stops 30 to properly position the drip board, and the continued frictional driving power serving to hold it in place.

While this invention is primarily conceived to use in connection with the power wringers on washing machines, its use may be extended to any type of wringer. It will be further apparent to those skilled in the art that the mechanical construction of my invention as shown in the accompanying drawings represents only one of a number of possible designs for an automatically reversible drip board, many others of which are known to the inventor, and any variations in the design will not interfere with the priority of my broader claims to the invention.

What I claim as new is:—

1. In a wringer, the combination of a frame; rolls mounted in the frame; a tilting drip board; a shaft on which the drip board is mounted; a bearing for the shaft; a friction roll on the shaft; a friction roll driven with the wringer roll frictionally engaging the first-mentioned friction roll;

and stops limiting the movement of said shaft to position the drip board.

2. In a wringer, the combination of a frame; wringer rolls; shafts for the rolls mounted in and extending through the frame; a tilting drip board; a shaft on which the drip board is mounted, said shaft extending through the frame; and means

outside of the frame forming a driving connection between a wringer roll shaft and 10 said drip board shaft for reversing the tilting drip board as the wringer rolls are reversed.

In testimony whereof I have hereunto set my hand.

JOHN R. SPENCER.
